UNITED STATES PATENT OFFICE.

ANNIE SCOTT, OF WEST KENSINGTON, LONDON, ENGLAND.

VALVE-GEAR FOR INTERNAL-COMBUSTION ENGINES.

1,383,163.

Specification of Letters Patent. Patented June 28, 1921.

Application filed July 17, 1920. Serial No. 397,042.

(GRANTED UNDER THE PROVISIONS OF THE ACT OF MARCH 3, 1921, 41 STAT. L., 1313.)

To all whom it may concern:

Be it known that I, ANNIE SCOTT, a subject of the King of Great Britain and Ireland, residing at 55 Perham road, West 5 Kensington, in the county of London, England, have invented a new and useful Valve-Gear for Internal-Combustion Engines, for which I have filed an application in Great Britain on Feb. 24, 1919, for Patent No. 10 138,183, and of which the following is a specification.

This invention relates to valve gear for valves of the shuttle type for internal combustion engines and has for its object obtaining a perfect valve action which is positive and noiseless in action and dispenses with the usual mechanical gear. A further object of this invention is to prevent fluttering or bouncing of valves of this type.

20 I attain these ends by actuating the valves by compressed air and by the exhaust gases from the working cylinders, by utilizing the working cylinders and their pistons as distributing valves for compressed air and 25 gases and by the creation at certain times in the cycle of increased friction on the shuttle valves.

In the accompanying drawing which shows by way of example the application of 30 this invention to a four cylinder engine working on the Otto cycle:—

Figures 1 and 2 are views in sectional side and end elevation of the cylinders showing the various ports.

35 Fig. 3 is a view in sectional plan on line $\alpha\alpha$ Fig. 1.

Fig. 4 is a view on an enlarged scale of one of the working cylinders and pistons.

40 Figs. 5 and 6 are diagrams showing the connections between the several working cylinders and the several valve cylinders.

Fig. 7 is a view of the working cylinders in sectional elevation showing the pistons in their relative positions when the valves are 45 in the positions shown in the diagrams Figs. 5 and 6, and,

Fig. 8 is a view on an enlarged scale of the device for creating additional friction on the valves.

50 Throughout the views similar parts are marked with like letters of reference.

On each of the working cylinders a —preferably on opposite sides—are mounted horizontally disposed valve cylinders b and

c for the inlet and exhaust valves respectively said valves being of the shuttle type. At or about the center of the length of each of the valve cylinders b are a pair of ports d and d' the former of which is in communication with the carburetor and the latter 60 of which is in communication with the inlet port a' of the working cylinder. The valve cylinders c each have similar ports e and e' the former in communication with the atmosphere and the latter in communication 65 with the exhaust port a^2 of the working cylinder.

The piston valves f and g are made in the form of spools and each is of such a length that the space between the end parts of each 70 is sufficiently long to fully open the ports d and d' , e and e' and one of said end parts is sufficiently long to close said ports.

In each inlet valve cylinder b are four ports two h and h' for the admission of the 75 compressed air for the operation of the shuttle valve f in same to open and close it respectively and two exhaust ports h^2 open to the atmosphere.

In each exhaust valve cylinder c are similar ports k , k' and k^2 which function in a similar manner to the ports h , h' and h^2 to operate the shuttle valve g to control the exit of the exhaust gases from the working cylinder. The exhaust ports h^2 and k^2 are 85 so located that a certain amount of air or gas is trapped for cushioning purposes.

In each of the working cylinders a at or near the lower end thereof, are five ports four of which are arranged in two pairs diametrically opposite to one another. One pair of ports m and m' —hereinafter called the "valve-operating" ports—are arranged a short distance above the other pair of ports n and n' —hereinafter called the "charging 95 ports." The other port o —hereinafter called the "exhaust gas port"—is arranged in a suitable position above the ports m and m' .

In the piston p of each working cylinder is formed a chamber p' out of which leads—100 through the wall of the piston—two diametrically opposed ports r and r' hereinafter called the "distributing ports." These ports as the piston approaches the lower end of its cylinder first register with the valve-operating ports m and m' and a little later with the charging ports n and n' the location 105 of said two series of ports relative to

the stroke of the piston and to one another, and the position of the distributing ports r and r in the piston relative to the head of the piston, being such that (1) the valve 5 operating ports m and m are not at any time put into communication with the charging ports n and n ; (2) when the distributing ports r and r are registering with the charging ports n and n the valve-operating 10 ports m and m are not uncovered by the piston, and (3) the valve-operating ports m and m and the charging ports n and n are never uncovered by the piston so as to open same to the working cylinder.

15 The valve-operating ports m in each working cylinder are connected by one or more suitable passages or pipes m^1 to the port h of the inlet valve cylinder and to the port h^1 of the exhaust valve cylinder of a different working cylinder and to the port h^1 of the inlet valve cylinder of yet another different working cylinder said connections being determined by the sequence of firing.

20 The charging ports, n , of each working cylinder are connected by suitable passages or pipes, n^1 , with the compressed air chambers or containers—diagrammatically shown by, n^2 , in Fig. 2—which may be of any suitable type. The containers are kept charged 25 by a piston, w , operating in a chamber, w^1 . This chamber is closed by a cap when in use and the piston is arranged to control the inlet port, w^4 , which is open to atmosphere, and the exhaust port, w^5 , communicating, 30 by a pipe, w^6 , with the container. The piston, w , is operated by any suitable means such as, through an eccentrically operated rod, w^3 , from the crank shaft of the engine.

35 The exhaust gas port o in each working cylinder is connected by a suitable passage or pipe o^1 with the port h of its own exhaust valve cylinder. All other conditions being equal it is preferred to so arrange the sequence of firing as to make the connecting 40 passages or pipes m^1 , n^1 and o^1 as short as possible.

45 The operating of the valve gear in which the order of firing in the cylinders is 1, 2, 3, 4, is as follows:—

50 On the induction stroke of say No. 1 working cylinder, as the working piston approaches the end of the induction stroke the distributing ports r in said piston register with the valve-operating ports m and put 55 the chamber p^1 in the piston p into communication with the ports h^1 and h of the inlet valve cylinders b of Nos. 3 and 4 working cylinders and with the port h^1 of the exhaust valve cylinder c of No. 4 working cylinder, but as the pressure in said chamber after the distributing ports in the piston have passed the valve operating ports on the upward stroke of the piston is at or near atmospheric pressure no action of said valves 60 takes place. When the working piston

reaches the end of the induction stroke the distributing ports r register with the charging ports n thereby allowing compressed air from container to pass into the chamber of the piston. During the induction stroke the 70 working piston will have uncovered the exhaust gas port o but as the pressure in the working cylinder at the time of opening is at or below atmospheric pressure the exhaust valve will not be operated. As the 75 working piston commences its compression stroke the distributing ports r again register with the valve-operating ports m which put the chamber of the piston again in communication with the ports h^1 and h of the valve 80 cylinders b of No. 3 and No. 4 working cylinders and with the port h^1 of the exhaust valve cylinder c of No. 4 working cylinder. As, however, the working piston of No. 3 cylinder is on its exhaust stroke the inlet 85 valve of said cylinder is closed and consequently the exhaust port h^2 in the valve cylinder is open which allows the compressed air to escape. Further, as the working piston of No. 4 cylinder is on its firing stroke 90 both the inlet valve and the exhaust valve of said cylinder are closed and the pressure of the compressed air reduced by reason of the open passage h^2 through the inlet valve cylinder of No. 3 working cylinder will be 95 insufficient to operate said inlet and exhaust valves against the pressure in the working cylinder acting on them.

95 As the working piston reaches the end of its firing stroke, the distributing ports r again register with the valve-operating ports m but as the pressure in the chamber of the piston has already been exhausted, as before described on the compression stroke, no action of either the inlet valves of No. 3 and 100 No. 4 working cylinders or the exhaust valve of No. 4 working cylinder takes place. At the end of firing stroke the distributing ports r again register with the charging ports n and the chamber of the piston again 105 becomes charged with compressed air from the external container. When the exhaust gas port o in the working cylinder is uncovered by the piston during this stroke the pressure within the working cylinder passes 110 to the cylinder of the exhaust valve of said working cylinder and opens it due to the area of the valve exposed to the pressure in the valve cylinder being greater than the area of the valve exposed by the port a^2 to 115 the pressure in the working cylinder.

120 On the exhaust stroke of the working piston when the distributing ports r register with the valve operating ports m the compressed air from the chamber in the piston passes once more to the inlet valve cylinders of Nos. 3 and 4 working cylinders and to the exhaust valve cylinders of No. 4 working cylinder this time operating to close the inlet valve of No. 3 cylinder which at the com- 125

mencement of this stroke was open, to open the inlet valve of No. 4 cylinder and to close the exhaust valve of No. 4 cylinder which at this point of the cycle are not under pressure 5 from the working cylinder.

It will be seen that the valves *f* and *g* are only operated during the exhaust strokes of one of the working cylinders and that on the other strokes no effective work is done 10 because of the positions of the valves in their respective cylinders.

Between each of the valve cylinders *b* and *c* and the adjacent working cylinder is a recess *s* which is in axial alinement with the 15 valve cylinder and through which the ports *a*¹ and *a*² pass. In these recesses are sliding plates *t* adapted to move with the valves *f* or *g* and to cover and uncover the ports *d* or *e* between the valve cylinders and the working 20 cylinders. The connection between the sliding plates *t* and the piston valves *f* or *g* is such that said plates partake of the movement of said valves but are free to move radially or transversely in relation thereto so 25 that they are free to take a bearing on either of the faces of the recesses *s* in which they work. A convenient coupling is that shown which consists of a pin *v* carried by the plate *t* and adapted to engage—by an easy 30 fit—with a radially arranged hole in one of the end parts of the valve. The size of the sliding plates *t* is such that when they are pressed up against one or other of the faces of the recesses *s* by reason either of the pressure 35 or the suction in the working cylinders sufficient friction is created to prevent the piston valves—which as before stated are coupled to them—from fluttering or bouncing at the ends of their strokes and further 40 the area of plates *t* exposed to internal pressure of working cylinders must be less than the areas of the end parts of the valves which are actuated to open the exhaust valves only. The preferred construction is 45 to so arrange the sliding plates in relation to the valves that said plates close the ports between the working cylinders and the valve cylinders when said ports are closed by the valves so that said valves are not subjected 50 to either the flame or pressure arising from the firing of the working charge in the working cylinders.

It will be apparent that the ports *m* and *n*

are only duplicated in each working cylinder for convenience in construction as a single port will suffice if it and its connections are made large enough. 55

What I claim is:—

1. In a valve gear for internal combustion engines the combination of four working cylinders or multiples thereof with inlet and exhaust valves of the shuttle type the former operated entirely by compressed air and the latter operated partly by compressed air and exhaust gases from the working cylinder 65 whose pistons act as distributors.

2. In a valve gear for internal combustion engines the combination with four working cylinders of valve cylinders mounted on the side of the working cylinders, of valves of 70 the shuttle type within the valve cylinders, of sliding plates between the working and valve cylinders and attached to the valves, of inlet and exhaust ports within said valve cylinders and ports within the pistons of the 75 working cylinders receiving and distributing compressed air to the valve cylinders.

3. In a valve gear for internal combustion engines the combination with four working cylinders of valve cylinders mounted on the 80 side of the working cylinders, of valves of the shuttle type within the valve cylinders, of sliding plates between the working and valve cylinders and attached to the valves, of inlet and exhaust ports within said valve 85 cylinders, ports within the pistons of the working cylinders receiving and distributing compressed air to the valve cylinders and chambers within said pistons.

4. In a valve gear for internal combustion 90 engines the combination with four working cylinders of valve cylinders mounted on the working cylinders, of valves of the shuttle type within the valve cylinders, of sliding plates between the working and valve cylinders and attached to the valves, of inlet and exhaust ports within said valve cylinders and ports within the pistons of the working cylinders receiving and distributing compressed air to the valve cylinders, of containers 95 for receiving the compressed air and pipes for conveying the compressed air from one part of the engine to another. 100

Dated this 28th day of June, 1920.

ANNIE SCOTT.
